PROCESS OF REFINING OIL

Benjamin H. Thurman, Bronxville, N. Y., assignor
to Refining, Inc., Reno, Nev., a corporation of
Nevada

Application February 25, 1938, Serial No. 192,654

11 Claims. (Cl. 260—425)

This invention relates to a process of refining oil, and more particularly to a process for alkali refining animal and vegetable oils.

Animal and vegetable oils have been conventionally refined by mixing therewith a caustic alkali solution of a concentration and in an amount determined from long experience in refining such oils in order to form soap stock which was allowed to settle from the oil. This process was carried on in large open kettles often holding as much as sixty thousand pounds of oil. The oil was first placed in the kettle and the alkali then added in sufficient amounts to neutralize the free fatty acids of the oil and provide a large excess for reaction with color impurities and for forming a soap stock which would effectively settle from the oil. The addition of the alkali to the oil was performed at relatively low temperatures, i. e., 70 to 80° F., as the refiner had learned from experience that preheating a large body of the oil tended to set the colors therein, rendering them difficult or impossible to be removed in the refining process or subsequently. The oil and caustic mixture was vigorously agitated until a so-called "pin break" was obtained, indicating neutralization of the free fatty acids. The entire mixture was then heated by any suitable means, such as steam coils positioned in the kettle, and the rate of agitation reduced. Heating and slow agitation was continued until a "break" was produced, at which time agitation and heating were discontinued and the resulting soap stock allowed to settle from the oil. The oil was then drawn off, and further processed, for example by washing and vacuum drying, or clay treatment, to remove residual soap stock, alkali and water, and then, if desired, was subjected to bleaching and deodorization.

In order to obtain good color reduction and form a soap stock which would readily settle from the oil without excessive entrainment of oil, the refiner found it necessary to use a large excess of alkali. This large excess invariably caused saponification of substantial amounts of neutral oil, but was considered necessary, as above stated, for color reduction and the formation of a readily settleable soap stock. Because of the large excess and the resulting type of soap stock formed, it was necessary to discontinue agitation as soon as the "break" had occurred in order to prevent breaking up the particles of soap stock and beating them back into the oil, such that an inseparable emulsion would be formed. Attempts had been made to centrifugally separate the oil from the soap stock formed in such

refining operations, but if agitation were continued in order to keep the soap stock from stratifying into large masses which could not be handled by the centrifuge, a major portion of the soap stock was broken up and beaten back into the oil until centrifugal devices were ineffective to separate the soap stock from the oil.

In accordance with the present invention, it has been found that, by employing a much smaller excess, a soap stock is formed which is not broken up or beaten back into the oil by continued agitation after the break and yet color reduction can be accomplished by maintaining the mixture in a heated condition and agitating the same after the break. This can be accomplished without excessive saponification of the neutral oil because of the small excess. The resulting soap stock may be maintained in substantial even distribution by the continued agitation, and the resulting mixture of oil and soap stock can be centrifugally separated to produce a relatively clean oil. Such centrifugal separation markedly reduces the amount of oil entrained in the soap stock over the conventional batch settling step, such that the losses incurred in the process of the present invention are much less than those of the conventional batch refining process.

It is, therefore, an object of the invention to provide a process of refining vegetable and animal oils in which the soap stock is centrifugally separated from the oil and a smaller excess than that conventionally employed is utilized.

Another object of the invention is to provide a process of refining vegetable and animal oils in which the oil and refining reagent may be mixed in existing apparatus and the resulting soap stock centrifugally separated from the oil.

A further object of the invention is to provide a process of refining animal and vegetable oils in which the alkali employed in conventional processes is markedly reduced in order to prevent reemulsification of the soap stock under continued agitation.

A still further object of the invention is to provide a process of refining animal and vegetable oils in which the oil and alkali may be mixed in relatively large quantities and the resulting soap stock centrifugally separated from the oil.

Other objects and advantages of the invention will appear in the following description thereof made in connection with the attached drawings, of which:

Figure 1 is a diagrammatic view of an apparatus suitable for carrying out the invention; and

Figure 2 is a similar view of an apparatus suitable for carrying out a modified process.

Referring to the drawings, and more particularly to Figure 1, 8 and 9 indicate supply tanks for oil and refining reagent respectively; 10 and 11 indicate mixing and separation conditioning devices; 12 indicates a pump for delivering a mixture of oil and soap stock to a centrifugal separating system indicated generally at 13.

The mixing and conditioning devices 10 and 11 may be similar to the kettles employed in the conventional batch refining of oil and may each include a casing 14, an agitator 15 rotated from any suitable source of power by a pulley 16, and a heating coil 17. Provision is made for introducing oil and alkali into the mixers 10 and 11, for example by pipes 18 and 19 respectively. The oil can be heated to a flowable condition in the tank 8 by a heating coil 18 and a similar coil 19 can be provided in the tank 9 for bringing the refining reagent to a desired temperature. One of the mixers 10 and 11 can be employed for forming a mixture of oil and alkali while a similar mixture is being withdrawn from the other mixer and delivered by the pump 12 to the centrifugal separating system 13. The oil can be withdrawn from the mixer 10 through a pipe 20 provided with a valve 21 and from the mixer 11 through a pipe 22 provided with a valve 23. The pipes 20 and 22 join with a common pipe 24 at 25 so that, by opening one of the valves 21 and 23 and closing the other, the pump 12 will deliver the mixture through a pipe 25 for distribution to the centrifugal separators 27, 28 and 29, all of which can be employed simultaneously to increase the capacity of the refining system. Each of the centrifugals is provided with a spout 30 through which the oil is discharged as the lighter effluent into funnels 31, all connected to a common pipe 32, through which the oil may be delivered to conventional steps, such as washing and vacuum drying or clay treatment for removing residual alkali, soap stock and water. Each of the centrifugals may also be provided with a spout 33 through which the soap stock is discharged as the heavy effluent into any suitable receptacles 34. The centrifugal separators may be of any type capable of separating soap stock from oil and are preferably of the heated type disclosed in my Patent No. 2,100,276.

In carrying out the process of the present invention, a quantity of oil to be refined may be introduced into one of the mixing devices, such as the device 10. The devices 10 and 11 may be of extremely large capacity, if desired, such as the sixty thousand pound kettles above referred to, but are preferably of smaller capacity, for example, from a few hundred pounds up to eight or ten thousand pounds capacity. When introduced, the oil is preferably at approximately ordinary room temperature, that is, between 70 and 80° F., but this temperature, with various oils, may range between 60 and 90° F. Also, the refining reagent is preferably within such range of temperatures so that mixing is accomplished within such range. If the oil is not at the desired temperature, the heating coil 17 may be employed to raise the temperature of the oil to that desired. As stated before, it is undesirable to bring a large body of oil to an elevated temperature much above those above mentioned before adding alkali, as colors are thereby set in the oil, particularly in the case of cottonseed oil.

After the oil is introduced into the mixer 10, vigorous agitation is started by rotating the agi-

tator 15 and the correct amount of alkali solution, preferably caustic soda, is run in through the pipe 19. While the agitation should be vigorous in order to promptly mix the alkali solution with the oil, and at all times maintain a substantially uniform mixture thereof, it should not be sufficient to cause any substantial amount of air to be beaten into the mixture. It is also possible to simultaneously add the oil and reagent while running the agitator 15 in order to mix the materials as they are added.

The amount of alkali and the concentration of the alkali solution will depend upon the type of oil being treated, particularly its free fatty acid content. The amount of alkali necessary to neutralize the free fatty acids may be determined by known means by measuring the free fatty acid content of a sample of the oil. In conventional batch refining the amount excess over that necessary to neutralize the free fatty acids has been determined from rules and tables prepared for the use of refiners, and by the experience of the refiner performing the operation. As stated before, in conventional batch operations extremely large excesses are ordinarily employed, in many cases being two or three times the amount necessary to neutralize the free fatty acids. This large excess was considered necessary in order to effectively reduce the color when operating the conventional method of batch refining, and also in order to produce a soap stock which would readily settle from the oil without entraining excessive amounts of oil. However, even by employing such large excesses, the amount of oil entrained was greatly in excess of that present in the soap stock separated from the oil in the present invention. Also, the large excess caused much greater saponification of neutral oil than takes place in the present process, as one part of caustic soda will saponify more than seven parts of oil. Since the present process does not contemplate settling the soap stock from the oil, the large excess above referred to is not required, and, in fact, generally cannot be employed. An exact excess applicable to every oil cannot be given, as the necessary excess will vary with the type and quality of oil being treated. In general, it can be stated that the excess employed in accordance with the present invention is materially less than that necessary in conventional batch operations. The concentrations of the refining solutions, however, will ordinarily be similar to those conventionally employed in batch operations. The necessary concentration again depends upon the type and quality of oil being treated, and its free fatty acid content, and the refiner depends upon published rules and tables as well as his own experience in determining what concentrations should be employed.

When the correct amount of alkali has been added to the oil in the mixer 10, vigorous agitation is continued until the "pin break" is obtained, shown by the presence of small flocks of soap stock in a sample of the oil. The so-called "pin break" condition is a tight and difficultly separable emulsion which is predominantly of the water-in-oil type. In order to break this emulsion, heat is applied, for example by passing any desired heating medium, such as steam, through the heating coil 17. Heating and agitation is continued until the emulsion is broken, as shown by the condition of a sample of the mixture in which condition the soap stock is readily separable from the oil. The temperature at which the break occurs will also vary with different oils,

and their free fatty acid content, but ordinarily occurs between 100 and 160° F. and usually between 110 and 140° F.

Agitation is preferably somewhat reduced during the heating operation, and in accordance with the present invention is continued after the "break," as distinguished from conventional batch operations in which agitation is stopped as soon as the "break" is reached. As stated before, continued agitation after the "break" has been reached, in conventional batch processes employing a large excess would cause the soap stock particles to be broken up and finely dispersed in the form of an emulsion in the oil, rendering the same inseparable by settling or centrifugal separation. However, by employing the small excess of the present invention, the agitation can be continued to maintain the mixture substantially uniform without forming a difficultly separable emulsion. The amount of excess employed must be balanced against the time the mixture is maintained in the mixing device under agitation after the "break." If the mixing device has an extremely large capacity as compared to the amount of mixture which may be separated in a short time by the centrifugals employed, a smaller excess must be employed in order to prevent beating soap stock back into the oil. In other words, even with a small excess, the agitation cannot be continued indefinitely without rendering the mixture inefficiently separable. On the other hand, sufficient excess must be employed to produce the necessary color reduction. The longer the time of agitation after breaking, the less the excess which can be employed. Thus it is seen that the precise amount of excess employed with any given oil depends upon the nature of the oil and the relative capacities of the mixing devices and centrifugal separating devices. The relative capacities of the mixer and centrifugal should be such that in no case is continued agitation after the break necessary for more than two or three hours unless the excess contemplated by the present invention is much smaller than that necessary to form the easily settleable soap stock required in conventional batch refining. When employing the conventional batch excess, the separation must be performed in a much shorter time after the break than with the small excesses disclosed herein.

The nature of the agitation after the break has occurred is also of importance. Too violent agitation will form an inseparable mixture, more especially in an open kettle, even if small excesses are employed. Mechanical agitators of the general type disclosed in the drawing and provided with one or more impellers for causing relatively slow uniform agitation of the oil have been found effective, while other types of agitation such as those involving rapid recirculation of the mixture invariably produce inseparable emulsions. The agitation should be only that necessary to maintain the mixture of oil and soap stock in substantially uniform condition, that is in the substantially uniformly agglomerated condition resulting from slow agitation after the break and providing most effective separation, such that no stratification and formation of large masses of soap stock takes place. Such large masses of soap stock unbalance the fluid columns in the centrifugal separators, such that separation is not uniform and soap stock is discharged with the oil and oil with the soap stock.

It is evident that one mixer only may be em- 75

ployed in the present invention, but by employing two or more mixers in parallel continuous separation may be accomplished in the centrifugal separating system 13.

5 Since the mixture leaving the mixers 10 or 11 is in broken condition and at a suitable temperature for centrifugal separation, it may be delivered directly to one or more centrifugal separators. An exceptionally clean separation of the oil from the soap stock can be accomplished therein, such that entrainment of oil in the soap stock is markedly reduced over that accomplished in conventional batch operation. Also, the small excess employed during mixing markedly reduces the saponification of neutral oil. Thus the over all losses of the present process are much lower than those resulting from the conventional batch operation. An oil of good color is obtained despite the small excess employed and an efficient economical process obtained with substantially all vegetable and animal oils encountered.

20 Also, as shown in Figure 2, continuous mixing followed by a period of treatment similar to that in mixers 10 or 11 can be employed. Thus in Figure 2 oil may be pumped from a supply tank 35 therefor through a pipe 36 by a proportioning pump 37 to a mixer 38. The refining reagent may be pumped from a supply tank 39 through a pipe 40 by a proportioning pump 41 to the mixer 38. A heating coil 42 through which any desired heating medium, such as steam or hot water, can be circulated may be positioned in the oil supply tank 35 so as to keep the oil therein in a flowable condition, but in general it is not desirable to heat a large body of oil in the tank 35 to temperatures much above those necessary to render the oil readily pumpable. A similar coil 43 may also be positioned in the supply tank 39 for the refining reagent in order to bring this reagent to any desired predetermined temperature. The proportioning pumps 37 and 41 may be driven, for example, by a variable speed electric motor 44 and have a variable speed device 45 positioned 25 between the pumps so that any desired amounts and proportions of oil and refining reagent can be delivered to the mixer 38. The particular proportioning apparatus disclosed is by way of example only, and any other apparatus capable of pumping accurate predetermined proportions and amounts of oil and refining reagent can be substituted therefor.

25 If it is desired to preheat the oil prior to mixing, the oil may be passed through a flow heating device which may include a coil 46 positioned in a casing 47 through which any desired heating medium, such as steam or hot water, can be circulated by the pipes 48 and 49. Similarly, the refining reagent can be preheated prior to mixing by passing the same through a heating device including a coil 50 positioned in a casing 51 similar to the casing 47 surrounding the coil 46. The mixing device 38 may be any effective flow mixing device such as a mechanical agitator or a device in which a stream of one of the materials is injected at right angles into a stream of the other. The flow mixing device disclosed in my copending application Serial No. 190,673 filed February 15, 1938, now Patent No. 2,142,062, granted December 27, 1938, has been found to be extremely effective, and is preferred. A thorough admixture is accomplished in the mixing device 38 and this mixture may be delivered through a pipe 52 into a treating chamber 53.

The treating chamber 53 may include a closed

casing 54 surrounded by a heating jacket 55 and provided with an agitating and scraping mechanism 56 having a shaft 57 passing through a packing gland 58 and rotated from any suitable source of power by means of a pulley 59. Any desired heating medium, such as hot water or steam, may be circulated through the heating jacket by pipes 60 and 61. The agitator 56 may be of any suitable type which will maintain the mixture in the treating chamber in substantially uniform condition without beating the soap stock back into the oil to form a difficultly separable mixture, and is preferably provided with scrapers 62 contacting the walls of the casing 54 so as to remove therefrom any soap stock which may deposit upon the walls.

The mixture may be discharged through a pipe 63 and a pipe 64 connected to pipe 26, which may be the same as the pipe 26 of Figure 1, leading to one or more centrifugal separators 27 similar to those shown in Figure 1. If it is desired to further heat the mixture in order to bring it to that desired for optimum separating conditions, instead of passing the oil through the pipe 64 it may be passed through a heating device which may include a heating coil 65 positioned in a casing 66 through which any desired heating medium, such as hot water, may be circulated by means of the pipes 67 and 68. Thus, by closing the valve 69 in pipe 64 and opening the valve 70 in the pipe leading to the coil 65, the mixture may be passed through the heating coil, while it may be bypassed around the heating coil by opening the valve 70 and closing the valve 69.

In many cases, it has been found advantageous to introduce a heated diluting medium such as water or salt solution into the pipe 26 immediately before the mixture is delivered to the centrifugal separators. Thus, a pipe 71 provided with a valve 72 may be employed for introducing such a medium into the mixture. If desired, additional heat can be supplied to the mixture by introducing water or salt solution at a higher temperature than the mixture in the pipe 26 so as to promote separation in the centrifugal separators, but in any event the water or salt solution is separated with the soap stock and acts as a diluting agent therefore in order to render the same easily discharged from the separators. Any salt, such as a salt of an alkali metal, which has no deleterious reaction with the oil or soap stock, may be employed. Also, it is advantageous to add such a salt to the mixing and conditioning devices of Figure 1 or have the same present in the treating chamber of Figure 2, to harden the soap stock and make it more difficult to beat back into the oil.

In the modification of the invention disclosed with reference to Figure 2, the mixture formed in the mixer 38 may be introduced into the treating chamber 53 at relatively low temperatures, for example temperatures between 60 and 90° F., and heated in the treating chamber up to an emulsion breaking temperature during agitation therein. The treatment in the agitating chamber 53 is for the purpose of enabling the low excess discussed with reference to Figure 1 to be employed and still give sufficient time for color removal. Thus, the chamber 53 may be sufficiently large to provide a treating time of, for example, ten minutes to two hours, depending upon the nature of the oil being refined and the amount of excess employed. Alternatively, the oil or refining solution, or both, may be heated in the coils 46 and 69 to an emulsion breaking temperature such that no emulsion is formed in the

mixer 38 or, if formed, is broken substantially immediately after mixing. In this case, the mixture enters the treating chamber in an already broken condition and agitation is continued therein until desired color reduction has been produced with the low excess contemplated and the mixture then delivered to the centrifugal separators. As stated above, additional heat may be imparted to the mixture, if found desirable, in the coil 65. In many cases such additional heating is found desirable, as separation may be found more effective for a particular oil at a somewhat higher temperature than that found optimum for treatment in the treating chamber 53. Such a heating coil may, in some instances, also be employed prior to centrifugal separation and for the same purpose in the process practiced in the apparatus disclosed in Figure 1. As a still further modification of the process, the mixture may be maintained at a relatively low temperature below the emulsion breaking temperature, i. e. not substantially above 90° F. for most oils, in the treating chamber 53 and then the oil brought to an emulsion breaking temperature in the heating coil 65 and then delivered to the centrifugal separators for separation.

Although a closed treating chamber 53 has been disclosed and is preferable, it is possible to employ an open agitator tank as the treatment chamber, since the agitation in the treating chamber is only sufficient to maintain the mixture in relatively uniform condition and is insufficient to cause air to be beaten into the mixture. The process practiced in the apparatus of Figure 2 is essentially similar to that practiced in the apparatus of Figure 1, since a low excess, as compared to conventional refining, is employed and agitation may be continued after the break has been produced. In this process also, the refining losses are minimized because of the low excess and low entrainment of neutral oil in the soap stock. Effective color removal is likewise produced, even though a low excess is employed, as sufficient time is provided for color reaction.

Thus, the process of the present invention may be practiced with such oils as cottonseed, soya bean, corn, rape seed, as well as certain animal oils, in which is intended to be included fish oils such as herring, menhaden oil or sperm oil. It will be appreciated that this process will be found more particularly adapted for certain types of oils, for example the oils which may be classified as "slow breaking oils," or as "cold pressed oils." The present process is sufficiently flexible that any necessary time of treatment can be employed.

While I have disclosed the preferred embodiments of my invention, it is to be understood that the details thereof may be varied within the scope of the following claims.

I claim as my invention:

1. The method of refining animal and vegetable oils containing free fatty acids, which comprises: adding an alkali refining reagent to said oil in an amount sufficient to form an emulsion, neutralize the free fatty acids and reduce the color of the oil, but substantially less than that necessary when the soap stock is settled from the oil and insufficient to cause excessive saponification of neutral oil and beating of the soap stock back into the oil under prolonged agitation while the oil is in a heated condition; agitating said oil and reagent to mix the same; heating the mixture to break said emulsion while continuing sufficient agitation to cause the remaining color im-

purities to combine with the resultant soap stock; continuing agitation of the heated mixture in a relatively large vessel at a rate sufficient to prevent stratification of the mixture; withdrawing a stream of said mixture from said vessel during said continued agitation; delivering the same to a centrifugal separator; and separating said soap stock from said oil.

2. The process of refining animal and vegetable oils containing free fatty acids, which comprises: mixing an alkali refining reagent with a body of said oil in an amount which will neutralize the free fatty acids and provide an excess sufficient to reduce the color of the oil during prolonged agitation under heated conditions but substantially less than that required to form a readily settleable soap stock; heating the resulting mixture to a temperature which will render said mixture separable by centrifugal separation; agitating the heated mixture in a relatively large vessel at a rate sufficient to prevent stratification but insufficient to form an inseparable emulsion; and delivering a stream of said mixture to a centrifugal separator wherein the resulting soap stock is separated from said oil.

3. The process of refining animal and vegetable oils containing free fatty acids and coloring impurities, which comprises: mixing an alkali refining solution with a body of said oil at a temperature between approximately 60 and 90° F. in order to form an emulsion, said refining reagent being added in amount sufficient to neutralize the free fatty acids and provide an excess for color reduction which is materially less than that necessary for forming a soap stock which can be settled from the oil; agitating said mixture and heating the same to an emulsion breaking temperature to break said emulsion; continuing said agitation in a relatively large vessel after the emulsion has been broken at a rate sufficient to maintain the mixture substantially uniform without beating said soap stock back into said oil; and withdrawing a stream of said mixture and subjecting the same to centrifugal separation to separate said soap stock from said oil.

4. The process of refining animal and vegetable oils containing free fatty acids and color impurities, which comprises: mixing an alkali refining reagent with said oil in sufficient amounts to neutralize the free fatty acids and provide an excess sufficient to reduce the color of the oil during agitation under heated conditions but which is substantially less than that required to form a readily settleable soap stock and insufficient to substantially attack the neutral oil; agitating a body of the resulting mixture in a relatively large vessel at an emulsion breaking temperature at the rate providing effective agglomeration but insufficient to produce an inseparable emulsion for sufficient time to cause reaction of said excess with a substantial portion of said color impurities; and delivering a stream of said mixture at a substantially uniform and regulated rate to a centrifugal separator wherein the resulting soap stock is separated from said oil.

5. The process of refining animal and vegetable oils, containing free fatty acids and coloring material, which comprises: mixing an alkali refining reagent with said oil in sufficient amounts to neutralize said free fatty acids and provide an excess for color removal which is insufficient to form a readily settleable soap stock; maintaining a relatively large body of said mixture at a temperature above the emulsion breaking temperature thereof in sufficient motion to prevent

the stratification of said mixture while providing for reaction of said excess with said coloring materials and conditioning the mixture for centrifugal separation, and thereafter continuing the motion of said body of mixture sufficient to prevent stratification but insufficient to beat the soap stock back into the oil while withdrawing a stream of said mixture and centrifugally separating the resulting soap stock from refined oil.

6. The process of refining animal and vegetable oils containing free fatty acids, which comprises: mixing with said oil an alkaline refining reagent in sufficient amounts to neutralize said free fatty acids and provide an excess which is substantially less than that required to form a settleable soap stock and sufficiently small that the resulting mixture of oil and soap stock may be agitated for a prolonged period of time when in a condition for centrifugal separation without forming an inseparable mixture; maintaining a body of said mixture at a temperature sufficiently high to condition the same for centrifugal separation; agitating said mixture for a relatively long period of time at said temperature at a rate sufficient to maintain the mixture relatively uniform but insufficient to produce an inseparable emulsion; withdrawing a stream of said mixture from said body; and continuously centrifugally separating the soap stock from the oil in said stream.

7. The process of refining animal and vegetable oils containing free fatty acids, which comprises: bringing a metered stream of said oil into contact with a metered stream of an alkali refining reagent in sufficient amount to neutralize said free fatty acids and provide an excess which is substantially less than that required to form a settleable soap stock; delivering the resulting stream into a relatively large body of oil; agitating said relatively large body of oil at a rate sufficient to prevent stratification of soap stock resulting from the neutralization of said free fatty acids but insufficient to cause an inseparable emulsion to be formed and at a temperature sufficiently high to condition the resulting mixture for centrifugal separation; withdrawing a stream of said mixture from said body of oil during agitation thereof; delivering the stream of mixture to a centrifugal separator; and continuously centrifugally separating said soap stock from said oil.

8. The process of refining animal and vegetable oils containing free fatty acids, which comprises: bringing a metered stream of said oil into contact with a metered stream of an alkali refining reagent in sufficient amount to neutralize said free fatty acids and provide an excess which is substantially less than that required to form a settleable soap stock; delivering the resulting stream into a relatively large body of oil; heating said body of oil to a temperature which will facilitate centrifugal separation while agitating the same at a rate sufficient to prevent stratification of soap stock resulting from the neutralization of said free fatty acids but insufficient to cause an inseparable emulsion; withdrawing a stream of said mixture from said body during said agitation; delivering the stream of mixture to a centrifugal separator; and continuously centrifugally separating said soap stock from said oil.

9. A process of refining animal and vegetable oils containing free fatty acids, which comprises: bringing a metered stream of said oil at a temperature which will facilitate subsequent centrifugal separation of soap stock from the oil

into contact with a metered stream of an alkali refining reagent in sufficient amount to neutralize said free fatty acids and provide an excess which is substantially less than that required to form a settleable soap stock; delivering the resulting heated stream into a relatively large body of oil; agitating said body of oil at a rate sufficient to prevent stratification of the soap stock resulting from the neutralization of said free fatty acids but insufficient to cause an inseparable emulsion to be formed while at a temperature which will facilitate centrifugal separation; withdrawing a stream of said mixture from said body of oil during said agitation; delivering the stream of said mixture to a centrifugal separator; and continuously centrifugally separating the said soap stock from said oil.

10. The process of refining animal and vegetable oils containing free fatty acids and coloring matter, which comprises: bringing a metered stream of said oil into contact with a metered stream of an alkali refining reagent in sufficient amount to neutralize said free fatty acids and provide an excess for reaction with said coloring matter which is substantially less than that required to form a settleable soap stock and insufficient in amount to cause an inseparable emulsion to be formed during prolonged agitation of the resulting mixture; delivering the resulting 20 stream into a relatively large body of oil; agitating said relatively large body of oil at a rate sufficient to prevent stratification of soap stock

5 resulting from the neutralization of said free fatty acids and at a temperature which will condition the mixture for centrifugal separation while providing time for reaction with said coloring matter; withdrawing a stream of said mixture from said body of oil during said agitation; delivering a stream of mixture to a centrifugal separator; and continuously centrifugally separating said soap stock from said oil.

10. The process of refining animal and vegetable oils containing free fatty acids and color impurities, which comprises: mixing an alkali refining reagent with a relatively large body of oil in an amount sufficient to neutralize said free fatty acids and provide a low excess for reaction with said color impurities, the excess of said refining reagent being substantially less than that required to form a settleable soap stock and insufficient to saponify substantial quantities of said oil; agitating the resulting body of mixture at a rate sufficient to prevent stratification of soap stock resulting from the neutralization of said free fatty acids but insufficient to cause an inseparable emulsion to be formed and at a temperature sufficiently high to condition the mixture for centrifugal separation; withdrawing a 25 stream of said mixture from said body of oil during said agitation; delivering the stream of mixture to a centrifugal separator; and continuously centrifugally separating said soap stock from said oil.

BENJAMIN H. THURMAN.
